[57] **CLAIM**

The ornamental design for a digital audio disc player combined with radio receiver, as shown and described.

DESCRIPTION

FIG. 1 is a perspective view of a digital audio disc player combined with radio receiver showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational thereof;

FIG. 7 is a rear elevational view thereof; and,

FIG. 8 is a perspective view thereof, wherein the lid portion is in the open position. The broken lines showing the insides of the digital audio player combined with radio receiver are for illustrative purposes only and form no part of the claimed design.

The inside of the digital audio disc player combined with radio receiver which is not visible on FIG. 8 forms no part of the claimed design.
